F. F. FISCHER

MEMORIAL GRAVE MARKER

Filed May 3, 1928

FIG. 1.

FIG. 2.

Frank F. Fischer

INVENTOR.

Patented Nov. 27, 1928.

Des. 76,994

UNITED STATES PATENT OFFICE.

FRANK F. FISCHER, OF OKLAHOMA CITY, OKLAHOMA.

DESIGN FOR A MEMORIAL GRAVE MARKER.

Application filed May 3, 1928. Serial No. 26,559. Term of patent 3½ years.

To all whom it may concern:

Be it known that I, FRANK F. FISCHER, a citizen of the United States, residing at Oklahoma City, in the county of Oklahoma and State of Oklahoma, have invented a new, original, and ornamental Design for Memorial Grave Markers, of which the following is a specification, reference being had to the accompanying drawing, forming part thereof.

Fig. 1 is a front elevational view of a memorial grave marker, showing my new design.

Fig. 2 is a side elevational view thereof.

I claim:

The ornamental design for a memorial grave marker, as shown.

FRANK F. FISCHER.
